GROMMET APPLYING TOOL WITH RESILIENTLY URGED LONGITUDINALLY SHIFTABLE UPSETTING ELEMENT

Joseph W. Wiesmann, Pittsburgh, Pa., assignor to H. H. Robertson Company, Pittsburgh, Pa., a corporation of Pennsylvania

Application March 8, 1949, Serial No. 80,135

6 Claims. (Cl. 218—25)

1

This invention relates to a tool and particularly to a grommet applying tool.

The invention has for an object to provide a novel and improved grommet applying tool particularly adapted for the installation of a grommet about the edges of an opening to be bushed characterized by upper and lower cooperating members for engagement with opposite edges of the grommet and which is designed to permit entrance of the lower cooperating member through the opening to be bushed whereby to facilitate the installation of grommets in relatively inaccessible places.

With this general object in view and such others as may hereinafter appear, the invention consists in the grommet applying tool hereinafter described and particularly defined in the claims at the end of this specification.

In the drawings illustrating the preferred embodiment of the invention, Fig. 1 is a front elevation, partly in cross-section, of a grommet applying tool embodying the present invention showing the tool in operative position to apply a grommet; Fig. 2 is a side elevation, partly in cross-section of the tool shown in Fig. 1; Fig. 3 is a detail view in cross-section showing the tool in position with the grommet applied about the edges of an opening, and Fig. 4 is a bottom plan view of the lower portion of the tool.

In general, the present invention contemplates a novel grommet applying tool particularly adapted for use in crimping or spinning a grommet about the edges of an opening formed in a metal sheet to provide a bushed opening and is particularly useful for bushing an opening in a wall of a closed duct, such as a duct employed for carrying wires in an underfloor wire distributing system. Such a duct and the opening to be bushed are disposed a substantial distance below the floor surface and are accessible from but one side thereof so as to prevent the introduction of a cooperating applying member larger than the opening itself into the interior of the duct and wherein also the access opening through the floor is usually limited in size so as to render it difficult to manipulate a hand tool, such as a pair of pliers for crimping the grommet into place, or such as to permit but limited manipulation of the tool laterally in the access opening when inserting or removing the tool into or from operative grommet applying position.

To this end the present tool comprises, in general, an elongated unit having an upper die section adapted for cooperation with the upper portion of a grommet placed in the opening to be

2

bushed, and a cooperating crimping or spinning roller revolvably carried by a central elongated rod mounted for extension and rotation in the upper die section arranged to be extended and introduced through the opening and into a position below the lower edge of the grommet and then retracted or elevated into engagement with the edge of the grommet and rotated to perform the bushing operation in cooperation with the upper die section. In practice, the tool may be lowered into the access opening through the floor and held in an offset or slightly tilted position relative to the underlying opening to be bushed to permit entrance of the extensible portion carrying the revolvable roller through the opening whereupon the tool may be moved laterally and into a vertical position into alignment with and concentric to the opening to dispose the tool in operative position to the lower edge of the grommet. The extensible portion of the tool is then retracted to dispose the roller in engagement with the lower edge of the grommet and to permit it to be rotated to perform the bushing operation. Provision is also made in the preferred embodiment of the invention for aligning the tool vertically with the opening and for supporting and maintaining the tool in such alignment to assure vertical axial rotation of the tool during the applying operation. Upon completion of the grommet applying operation the tool may again be extended, tilted slightly and moved laterally to permit withdrawal of the revolvably mounted roller unit from the bushed opening.

Referring now to the drawings, the present grommet applying tool comprises in general an elongated tubular support or sleeve 10 having a die member 12 at its lower end adapted for cooperation with the upper portion of a grommet inserted in the opening to be bushed, and an elongated central rod 14 slidably and rotatably mounted in the sleeve 10 and provided with a crank arm 16 at its lower end carrying an upsetting crimping or spinning roller 18 adapted to be inserted through the opening and engaged with the lower edge of the grommet to perform the applying operation upon rotation of the central rod 14.

As herein shown, the die member 12 comprises a circular disc having an annular groove 20 in the underside thereof for cooperation with the preformed rolled edge 22 of a grommet 24 placed in an opening formed in a metal sheet, herein shown as formed in the lower wall 26 of a closed cross over duct 28 and in the adjacent upper wall 30 of an underlying duct or cell 32 communicating with the cross over duct and forming a

part of an underfloor wire distributing system. The spinning roller 18 is rotatably mounted on a stud 34 carried in the end of the crank 16, the crank being herein shown as formed integrally with the central rod 14 and extended at right angles thereto so that upon rotation of the rod 14 the roller 18 will revolve about the central axis and in a path corresponding to the annular groove 20 in the disc 12. The central rod 14, slidably mounted in the sleeve 10 is extended upwardly beyond the end of the sleeve and provided at its upper end with a collar or hub member 38 secured to the rod by a pin 40, and an operating crank 42 attached to the upper face of the hub is provided with a handle 44 for manually rotating the rod in the sleeve.

Provision is made for extending and retracting the rod 14 in the sleeve 10 to present the spinning roller 18 into and out of operative engagement with the grommet during the operation of the tool, and as herein shown, a spring 46 coiled about the rod and interposed between the upper end of the sleeve and a washer 48 in engagement with the underside of the hub 38 is arranged to urge the rod upwardly to present the spinning roller 18 into operative engagement with the grommet. A latch member 50 pivotally mounted at 52 in an offset extension 54 attached to the upper end of the sleeve 10 by screws 56 is arranged to engage the upper end of the hub member 38 to normally maintain the spring 46 in a compressed or loaded condition and to retain the rod and the spinning roller in an extended position out of operative engagement with the grommet.

In order to facilitate compression of the spring 46 and to effect extension of the rod in the sleeve, the operating crank 42 is extended laterally an equal distance on both sides of the hub 38 and a pair of handle bars 58 attached to opposed sides of the sleeve 10 provide laterally extended arms arranged with respect to the operating crank arms so that when the upper and lower arms are in vertical alignment, as shown in Figs. 1 and 2, the arms may be grasped by the operator and squeezed toward each other to compress the spring until the desired position of extension is reached, whereupon the latch member 50 may be rocked on its pivot, from the dotted to the full line position shown in Fig. 2, into position to engage with an annular grooved portion formed in the top of the hub member 38. The handle bars 58 may also be used for manually holding the sleeve 10 stationary while rotating the crank arm 42 during operation of the tool.

From the description thus far it will be seen that when the tool is retained in its extended position by the latch 50, the spinning roller 18 and crank arm 16 may be introduced into and through the opening to be bushed by holding the tool in an offset or slightly tilted position relative to the opening since the combined length of the crank arm 16 and roller 18 is less than the diameter of the hole to be bushed. Thereafter, the tool is moved into a vertical position in alignment with the opening and the upper die member 12 is fitted over the preformed upper portion of the grommet, as illustrated in Figs. 1 and 2. When thus disposed, the latch member 50 is rocked to release the loaded spring 46 which operates to retract the rod 14 and to urge the revolubly mounted roller 18 into engagement with the lower edge of the grommet 22 and upon rotation of the rod 14, as above described, the grommet is crimped or spun into position, as shown

in Fig. 3. Thereupon, the tool may again be extended and latched into its inoperative position and moved laterally relative to the opening or tilted slightly so as to permit withdrawal of the tool.

As above described, the present construction of a grommet applying tool is of particular advantage when the opening to be bushed is disposed in a relatively inaccessible position, such as an opening formed in an underfloor wire distributing system, illustrated in Fig. 2, wherein the opening to be bushed may be disposed a substantial distance below the upper surface of the floor and the diameter of the opening in the floor may be limited in size so as to preclude the insertion and manipulation of the conventional hand tools for crimping the grommet into place. Such underfloor wire distributing systems are usually provided with access openings through the floor, as indicated at 60 in Figs. 1 and 2, formed at the intersection of the cross-over duct 28 and the underlying duct or cell 32, the access opening being herein shown as defined by an upstanding annular rim 62 formed in the upper wall of the cross-over duct and an adjustable telescopically mounted extensible member 64, the upper portion of which is arranged flush with the floor and provided with an annular recess 66 for receiving a removable cover, not shown.

When the tool is employed in an access opening as above described, the annular recessed portion 66 of the extensible member 64 may be utilized to provide a bearing for a centering disc 68 carried by the sleeve 10, the disc 68 being of a diameter such as to snugly fit into the recess 66 in order to centralize the tool and to assure vertical disposition of the tool during the grommet applying operation. As herein shown, the centering disc 68 is slidably mounted on the sleeve 10 and is guided vertically thereon by an elongated key 70 fast in the sleeve 10, as illustrated. In the operation of the tool, the disc 68 is held in a raised position, as indicated in dotted lines in Fig. 1, until the tool is inserted into operative position to the grommet and the centering disc may then be lowered into the recess 66 to maintain the tool in a vertical and central position during the applying operation. In order to facilitate raising and lowering of the disc 68 on the sleeve 10, a handle 72 may be provided on the upper surface thereof, or a finger opening 74 may be formed therein, as shown.

In practice, the recessed cover portion 66 of the member 64 is provided with equally spaced openings 76 for fastening the detachable cover thereto and as a further expedient for preventing rotary movement of the sleeve 10 during the grommet applying operation, one or more of the openings 76 may be utilized by providing aligned openings 78 in the keyed centering disc 68 and introducing a pin or key 80 through the aligned openings in the disc and cover receiving member. Thus, the keyed disc 68 may serve as both a centering member and a retaining member for the tool during the applying operation.

From the above description, it will be observed that the present grommet applying tool is simple in construction and efficient in operation and that the tool may be used with particular advantage in relatively inaccessible places such as when used for applying a grommet about an opening in the wall of a closed duct disposed a substantial distance below the surface of the structure in which the duct is installed and in

which access to the interior of the duct is limited by the size of the opening to be bushed.

While the preferred embodiment of the invention has been herein illustrated and described, it will be understood that the invention may be embodied in other forms within the scope of the following claims.

Having thus described the invention, what is claimed is:

1. A grommet applying tool for bushing an opening comprising a circular die member for engagement with the upper portion of the grommet, a roller for engagement with the lower edge of said grommet, means for operatively supporting the roller for movement toward and away from the die member, spring means for normally yieldingly urging the roller toward the die and into operative relation to the grommet, means for moving the roller away from the die to an extended position to permit insertion of the roller through said opening and into operative relation to said lower edge, latch means for restraining said spring means and for maintaining the roller locked in its extended position during the positioning of the tool, said roller being elevated toward said die and into pressing engagement with said lower edge by said spring means upon release of the latch of said locking means, and means for revolving the roller along said edge while maintained in said pressing engagement by said spring means to perform the grommet applying operation.

2. A grommet applying tool for bushing an opening comprising an elongated sleeve having a circular die member at its lower end for engagement with the preformed upper portion of a grommet inserted in said opening, an elongated rod slideable within said sleeve, a crank formed on the lower end of said rod and having a roller mounted thereon for engagement with the lower edge of said grommet, means for moving the rod longitudinally in the sleeve to an extended position to permit insertion of the crank and roller through said opening and into operative relation to said lower edge, spring means for yieldingly retracting the rod in the sleeve to urge the roller into pressing engagement with said lower edge, means for releasably locking said rod and roller in said extended position against the action of said spring means during the inserting operation, and means for rotating the rod to revolve the roller along said edge while said spring means is maintaining the roller in said pressing engagement to perform the grommet applying operation.

3. A grommet applying tool for bushing an opening comprising an elongated sleeve having a circular die member at its lower end for engagement with the preformed upper portion of a grommet inserted in said opening, an elongated rod slideable within said sleeve, a crank formed on the lower end of said rod and having a roller mounted thereon for engagement with the lower edge of said grommet, spring means for normally yieldingly urging the roller toward the die and into operative relation to the grommet, means for moving the rod longitudinally in the sleeve to an extended position to permit the introduction of the crank and roller through said opening and into operative relation to said lower edge by manipulation of the tool from an offset position to a vertically aligned position, a latch carried by said sleeve and engageable with the rod for restraining said spring means and for maintaining the roller in its extended position

during introduction of the tool in the opening, said roller being moved toward said die into pressing engagement with said lower edge upon release of the latch, and means for rotating the rod to revolve the roller along said edge while in said spring means is maintaining the roller in said pressing engagement to perform the grommet applying operation.

4. A grommet applying tool for bushing an opening in a member disposed a substantial distance below a fixed surface having an annular recess concentric with said opening comprising an elongated sleeve having a circular die member at its lower end for engagement with the preformed upper portion of a grommet inserted in said opening, an elongated rod slideable within said sleeve, a crank formed on the lower end of said rod and having a roller mounted thereon for engagement with the lower edge of said grommet, spring means for normally yieldingly urging the roller toward the die and into operative relation to the grommet, means for moving the rod longitudinally in the sleeve to an extended position to permit the introduction of the crank and roller through said opening and into operative relation to said lower edge by manipulation of the tool from an offset position to a vertically aligned position, a latch carried by said sleeve and engageable with the rod for restraining said spring means and for maintaining the roller in its extended position during introduction of the tool in the opening, said roller being moved toward said die into pressing engagement with said lower edge upon release of the latch, and means for rotating the rod to revolve the roller along said edge while said spring means is maintaining the roller in said pressing engagement to perform the grommet applying operation, and means on said sleeve above said die member for aligning and maintaining the tool concentric with said opening including a disc member carried by said sleeve and adapted for cooperation with said annular recess disposed above said opening.

45 5. A grommet applying tool for bushing an opening comprising, an upper die member and a lower upsetting member movable toward and away from said upper die member into and out of grommet applying position, means for moving the lower upsetting member away from the upper die member to an extended position to permit insertion of the lower upsetting member through said opening and into operative relation to the lower edge of the grommet, spring means for normally urging the lower upsetting member toward the upper die member and into pressing engagement with the lower edge of said grommet, means operable to restrain the action of said spring means and to releasably lock said lower upsetting member so that it is in its extended position during the inserting operation, and means for revolving the lower upsetting member, while said spring means is released to maintain said lower upsetting member in said pressing engagement, to perform the grommet applying operation.

6. A grommet applying tool for bushing an opening in a member disposed a substantial distance below a fixed surface and having an annular recess concentric with said opening comprising, an upper die member and a lower upsetting member movable toward and away from said upper die member into and out of grommet applying position, means for moving the lower upsetting member away from the upper die

member to an extended position to permit insertion of the lower upsetting member through said opening and into operative relation to the lower edge of the grommet, spring means for normally urging the lower upsetting member toward the upper die member and into pressing engagement with the lower edge of said grommet, means operable to restrain the action of said spring means and to releasably lock said lower upsetting member so that it is in its extended position during the inserting operation, means for revolving the lower upsetting member, while said spring means is released to maintain said lower member in said pressing engagement, to perform the grommet applying operation, and guide means above the grommet engaging portion of said upper die member including a vertically slidible disc adapted for cooperation with said annular recess for aligning and maintain-

ing the tool concentric with said opening during the grommet applying operation.
